UNITED STATES PATENT OFFICE.

ANDREW P. KELLER, OF TIFFIN, OHIO.

SPRAY DISK AND METHOD AND APPARATUS FOR MAKING THE SAME.

Application filed June 28, 1926. Serial No. 118,908.

This invention relates to spray heads such as are used for shower baths, and to procedure and apparatus for making the same, and more particularly to spray heads where-
5 in the spray-apertured portion or spray disk is formed of moldable material. It is de-
sirable that the spray apertures be so dis-
posed with relation to each other as to pro-
vide a divergence of the streams of water
10 from the axis of the head, so that a wide
shower may be caused to flow from a head of
comparatively small size, and heretofore
the common practice for obtaining this effect
has been to mold the spray disk without
15 apertures therein and subsequently to drill
cylindrical holes through it at the proper
angles to each other to provide the desired
divergence of their respective streams.

My chief objects are to provide an im-
20 proved spray head and to provide improved
procedure and apparatus for making it
whereby the apertures conveniently may be
formed in the disk by molding and yet may
be so disposed as to provide the desired
25 divergent spray effect. A further object is
to provide for giving the spray disk its gen-
eral shape and forming the divergent aper-
tures therein in the same molding operation.
A still further object is to provide for form-
30 ing the divergent apertures by means of a
unitary molding structure which may be
withdrawn from the molded product by
movement as a whole in an axial direction,
without movement of its parts with rela-
35 tion to each other. Another object is to pro-
vide for conveniently removing mold fins
from the mouths of the molded apertures.

Of the accompanying drawings:

Fig. 1 is a vertical section of a shower-
40 bath spray-head embodying and made by the
use of my invention in its preferred form.

Fig. 2 is a fragmentary top face view of
the apertured member or spray disk of the
head.

Fig. 3 is a vertical section of the apparatus
for molding the spray-apertured member.

Referring to the drawings, the head as
here shown comprises an upper bell portion
10 suitably secured and sealed to the usual
downwardly-projecting supply pipe 11 by
means of a yoke 12 screwed onto the end of
the pipe, a gasket 13 interposed between an
external flange 14 formed on the yoke and
an internal flange 15 formed on the bell,
55 and a gasket 16 interposed between the

flange 15 and a nut 17 screwed onto the
upper end of the yoke.

The spray and disk 18 of the head is
formed with an annular gasket-seating re-
cess 19 around the margin of its upper face 60
in which is seated an annular gasket 20
sealing the said member to the bell 10, the
apertured member 18 being supported and
drawn up to compress the gasket by a screw-
bolt 21 mounted in a central hole 22 in the 65
member 18 and screwed into the yoke 12.

The spray apertures in the member 18
are shown at 23, 23, and instead of being
cylindrical, as in such prior devices as I
am aware of, they are of downwardly ta-
pered, frusto-conical shape, but with their
axes downwardly diverging with respect to
the axis of the head, the axes of the aper-
tures more remote from the center of the
head being more divergent than those of the 75
apertures closer the center, as I find that
with the apertures so shaped and so disposed
the desired divergent spray effect may be
obtained and yet the apertures may be
formed by means of a unitary molding struc-
ture moving in an axial direction with re-
spect to the work both in the molding opera-
tion and in the withdrawal of the molding
structure, without movement of its aperture-
molding members with relation to each other 80
and without recession of the molding means
from the walls of the apertures in the course
of the molding, which permits desirable ap-
plication of full molding pressure to the
stock, and without interlocking of the mold-
ing means with the stock, such as would
90 cause breakage of the molded stock upon
the withdrawal of the molding means.

This form of the spray bottom permits the
molding thereof in a single molding operation 95
by means of the apparatus shown in Fig. 3,
which comprises an annular, female molding
member 24 rising from and secured by screw
bolts 25, 25 to a suitable bed plate 26, and
a pair of opposed male molding members 100
27, 28 telescoped therein, the upper male
member, 28, being secured by screw bolts
29, 29 to a movable press-head 30 and pro-
vided with dowels such as the dowel 31
adapted to run in suitable apertures in the 105
upper edge face of the female member 24 to
guide the upper male member 28 into and
out of the female member 24.

The lower male member, 27, is mounted
upon the upper ends of push rods 32, 32 110

which slidably extend through suitable apertures in the bed-plate 26 and have their lower ends secured to a yoke 33 provided with an actuating rod 34 for raising and lowering the lower molding member 27, which is thus adapted to act as an ejector for lifting the work out of the press after it is molded. Stop pins such as the pin 34^a are mounted in the bed-plate and are adapted to limit the downward movement of the lower male member 27.

A molding pin 35 having its base secured in the bed-plate 26 projects upward through a central aperture in the lower male member 27 and into a central aperture 36 in the upper male member 28, and is adapted to mold the central aperture in the spray disk 18 to receive the clamping bolt 21 (Fig. 1).

Secured in suitable apertures in the upper male molding member 28 are molding pins 37, 37 having frusto-conical, downwardly tapered end-portions 37^a, 37^a projecting from the lower or molding face of the member 28, the said pins being so disposed that their axes downwardly diverge from each other and preferably are disposed radially with respect to a common imaginary center above the assembly, but the divergence of the pins is so small with relation to the angle of the apex of their tapered portions 37^a that the latter may be embedded in the clay or the like of which the spray disk 18 is formed without interlocking therewith against free withdrawal, which requires that the angle of divergence of any pin with respect to the axis of the mold shall not be more than half the apex angle of its tapered end-portion.

After the molding operation, which will be obvious from the foregoing, thin mold fins usually are present at the lower mouths of the apertures molded by the pins 37, possibly because of imperfect fitting of the ends of the pins against the lower mold member 27 and because of the resistance to extrusion of the last thin layer of material under the end of the pin, but I find that such fins may be removed readily and without marring the surface of the work, so that the apertures will be of full size and regular form, by the simple step of lightly washing the lower face of the spray disk, as by passing a soft, water-saturated sponge over it, the fins freely melting or washing out, while the more substantial walls of the apertures are not appreciably affected.

The bell portion 10 of the head is of such form that it readily may be molded by the use of well-known apparatus. After the molding operations the parts 10 and 18, when made of clay, for example, are finished and hardened by the usual procedure, which may include glazing of the walls of the apertures as well as the other surfaces, and they are then assembled as shown in Fig. 1.

By reason of the tapered form of the apertures they readily may be cleaned in case of clogging, although their outlets are suitably small.

My invention thus provides the several advantages set out in the above statement of objects, and it is susceptible of modification without sacrifice of all of the said advantages and without departure from the scope of the appended claims. 75

I claim:

1. A molded spray head comprising a part formed with molded apertures tapered from the inner entirely to the outer surface of said part and having their axes outwardly diverging from each other. 80

2. The method of making a spray disk which comprises molding it with outwardly tapered spray apertures having their axes outwardly diverging from each other, by 85 forcing against a mass of stock, in an axial direction with relation to the disk, a set of outwardly tapered molding pins while holding the said pins with their axes outwardly diverging from the axis of the disk, and 90 while so holding the pins withdrawing them from the molded mass of stock.

3. The method of making an apertured disk which comprises so forcing a set of molding pins through a mass of plastic stock 95 against a molding member as to produce a disk substantially through-apertured but having mold pins within the apertures, the pins being so stopped by the said member that they do not project from the adjacent 100 face of the mass, and washing the surface of the product to remove mold fins from the mouths of the apertures molded by the pins.

4. Apparatus for molding a spray disk, the said apparatus comprising a mold member adapted to shape the outer face of the disk and molding means including outwardly diverging aperture-molding projections for molding the inner face and the apertures of the disk, the said mold member and the 110 said molding means being so constructed and arranged as to permit the said pins to be forced so far through the disk as substantially to make it through-apertured.

5. Apparatus as defined in claim 4 in 115 which the means for molding the inner face of the disk consists of a rigid, unitary structure and in which the axes of the projections outwardly diverge, each of the said projections being of such tapered form that the 120 molding means may be withdrawn in an axial direction from the molded disk without interlocking with the material thereof.

6. Molding apparatus comprising a face-molding member and a set of outwardly tapered mold pins projecting from the molding face of said member, fixed in relation thereto and having their axes outwardly diverging from each other, the pins being so 125 tapered with relation to their divergence as 130

to permit them to be forced in fixed relation as a group into a mass of stock without recession of their surfaces from the stock contacted thereby and to be withdrawn from the

5 molded mass without interlocking therewith.

7. The method of making a spray disk which comprises relatively forcing a set of molding pins so far through a mass of stock

as substantially to form through-apertures therein while so supporting the pins that in 10 a direction toward the stock they diverge from each other.

In witness whereof I have hereunto set my hand this 11th day of June, 1926.

ANDREW P. KELLER.
